UNITED STATES PATENT OFFICE.

DANIEL W. SHOYER, OF NEW YORK, N. Y.

DESIGN FOR HAMMOCK-CLOTH.

SPECIFICATION forming part of Design No. 36,792, dated February 9, 1904.

Application filed January 14, 1904. Serial No. 189,071. Term of patent 7 years.

To all whom it may concern:

Be it known that I, DANIEL W. SHOYER, a citizen of the United States, and a resident of the city of New York, borough of Manhattan, in the county and State of New York, have invented a new, original, and ornamental Design for Hammock-Cloth, reference being had to the accompanying drawing.

The figure is a plan view of a portion of hammock-cloth, showing my new design.

What I claim as new, and desire to secure by Letters Patent, is—

The ornamental design for hammock-cloth, as shown.

In testimony whereof I have signed my name to this specification in the presence of two subscribing witnesses.

DANIEL W. SHOYER.
